UNITED STATES PATENT OFFICE.

LUDWIG GUBA, OF DEJWITZ, NEAR PRAGUE, AUSTRIA-HUNGARY.

MEANS FOR SECURING RAILWAY-RAILS.

1,039,931.

Specification of Letters Patent.

Patented Oct. 1, 1912.

Application filed February 10, 1911. Serial No. 607,815.

To all whom it may concern:

Be it known that I, LUDWIG GUBA, a subject of the Emperor of Austria-Hungary, residing at Dejwitz, near Prague, Bohemia, in the Empire of Austria-Hungary, have invented certain new and useful Improvements in Means for Securing Railway-Rails, of which the following is a specification.

This invention has for its object to provide a clamping device for securing railway rails, consisting of two parts adapted to be adjusted relatively to one another, so as to exert a jamming and wedging action, one of which parts bears against the rail head and the other both against the rail foot and also against the means for attaching the rail to the sleepers, such as spikes, treenails and the like.

The invention is intended to prevent the rails shifting, the track spreading on curves, the spikes or treenails being forced or drawn out or loosened, the means for securing the rail and also the bed plate or ground plate and the rail foot being knocked out laterally, as for example being ground or worn off, the bed plate being prematurely pressed into the sleeper, more particularly where soft sleepers are used, and generally to improve the track structure by providing an absolutely solid and compact attachment of the rails to the sleepers.

The invention will now be described with reference to the accompanying drawings, in which it is shown by way of example:—Figure 1 being a cross section; and Figs. 2 and 3 side views of a rail provided in each case with an example of construction of the improved rail clamp; while Fig. 4 is a cross section; and Fig. 5, a side view of another form of construction of the rail clamp in combination with a railway rail.

In Figs. 1 to 3 two rail clamps are shown as applied one on each side of the rail. The two clamps are very similar, the principal difference being that the clamp shown in Fig. 1 at the left of the rail and in Fig. 2, is adapted to coöperate with two spikes; while the clamp shown in Fig. 1 at the right of the rail and in Fig. 3, is intended to co-operate with a single spike.

Referring to Figs. 1 and 2, the clamp at the left of the rail is shown as comprising members *a* and *b*, of which the member *a* bears against the head of the rail *c* while the member *b* engages with the foot of the rail, and with the heads of the spikes *h* *h*.

Between the members *a* and *b* are screw bolts *d* *d* which are mounted in the member *a* and project into recesses *e* *e* in the member *b*. These bolts *d* *d* carry nuts *f* *f* which engage the top of the member *b* and serve to adjust the effective length of the bolts *d* *d* in order to vary the distance between the members *a* and *b*. The member *b* has the cross-section shown in Fig. 1 and is provided on its bottom near its ends with notches or recesses *g* *g* which receive the heads of the spikes *h* *h* which help to secure the rail to the tie.

In the form of clamp shown at the right of Fig. 1 and in Fig. 3, the parts *a'*, *d'* and *f'* are substantially the same as the corresponding parts *a*, *d* and *f* in the clamp on the other side of the rail. And the member *b'* is similar to member *b* except for the fact that the member *b'* is provided with a single notch or recess *g'* which is located near the middle of the bottom of said member and receives the head of the spike or treenail *h'*.

The manner in which the clamps shown in Figs. 1 to 3 are applied will be obvious. After the clamp is introduced in place with the notches or notch in the member *b* or *b'* over the spike heads or head, the nuts *f* *f* or *f'* *f'* are set up by means of a wrench or spanner until the member *a* or *a'* is forced snugly against the bottom of the top of the rail *c*.

In the form of construction according to Figs. 4 and 5 both the upper part *a²* and also the lower part *b²* of the clamping device are wedge-shaped, and the clamping device is used in the following way:—The wedge-shaped lower part *b²* of the clamping device is placed, as in the forms of construction previously described, with its notches *g²*, *g²*, on the means for fastening the rails such as spikes or treenails *h²* *h²*, and with its lower part on the rail foot and then the upper part *a²* of the clamping device is driven laterally by means of a hammer, whereupon the relative position of both parts is fixed by a securing pin, which is passed through them. By the locking or jamming set up in this way between the rail and the means for securing the rail, full security is afforded against the shifting or creeping of the rails and, as experience has shown, four clamping devices only are sufficient for a rail ten meters in length, to prevent entirely shifting of the rail. Any weakening of the rail profile by notches or recesses is also en-

tirely avoided by the invention hereinbefore set forth.

I declare that what I claim is:—

1. A clamping device for railway rails comprising a member adapted to coöperate with the bottom of the head of the rail, another member adapted to rest on the rail foot and on the means which fastens the rail to the tie, the said members being adjustable 10 with reference to one another for different distances between the rail top and foot.

2. A clamping device for securing railway rails, comprising an upper part bearing against the head of the rail, a lower part bearing both against the rail foot and against the means for fastening the rail to the sleeper, the said device having notches therein to accommodate the said fastening means, and means for adjusting the said upper and lower parts relatively to each other so as to adapt them to exert a jamming and wedging action between the rail

and its fastening means, with different distances between the top and foot.

3. A clamping device for securing railway rails, comprising an upper part bearing against the head of the rail, a lower part bearing both against the rail foot and the spikes and treenails and having notches in the lower edge thereof to receive the heads of the rail spikes, and screws and nuts adapted to force apart the said upper and lower parts so as to produce a jamming and wedging action between the rail and its spikes and treenails with different distances between the rail top and foot.

In testimony whereof I have signed my name to this specification in the presence of two subscribing witnesses.

LUDWIG GUBA.
